J. I. ROBIN.
UPRIGHT GAS LAMP.
APPLICATION FILED DEC. 11, 1919.

Patented Aug. 31, 1920.

Inventor,
Jacob I. Robin
By his Attorney
Max H. Friedman

UNITED STATES PATENT OFFICE.

JACOB I. ROBIN, OF NEW YORK, N. Y.

UPRIGHT GAS-LAMP.

1,351,128.

Specification of Letters Patent. Patented Aug. 31, 1920.

Application filed December 11, 1919. Serial No. 344,079.

To all whom it may concern:

Be it known that I, JACOB I. ROBIN, a citizen of the United States of America, residing at Park avenue, 130th street, New York, in the county of New York and State of New York, have invented certain new and useful Improvements in Upright Gas-Lamps, of which the following is a specification.

10 The present invention relates to upright incandescent gas lamps and has for its principal object to simplify the construction of the burner and incandescent mantle and to enable the use of a rag or limp mantle on upright burners for ordinary city gas pressure.

While for inverted burners for ordinary city gas pressure the use of limp or rag mantles have for a considerable time been in general use in preference to shaped mantles by reason of the greater convenience of handling and shipping of the former, the use of limp mantles for upright burners has presented a more or less difficult problem. 25 With burners of the hitherto used construction the mantles require certain supports which engage the top of the mantle and in consequence of which dark or non-illuminated parts around the flame are produced. 30 These supports also are objectionable because of the increase of the cost of manufacture.

Another objection to this old construction is that in order to afford an exit for 35 the combustion gases the top of the mantle must be open and cannot be utilized for illuminating purposes.

Moreover, limp mantles could not be used with the burner as hitherto constructed for 40 ordinary city gas because the pressure of the gas mixture issuing from the top of the burner is directed only upwardly and is not strong enough to properly shape the mantle.

To obviate the drawbacks my invention 45 consists in an upright gas lamp in which the burner is so constructed that a top closed limp mantle slipped over the top of the burner will, on ignition, properly shape itself and produce an uninterrupted and 50 uniformly illuminated surface around and above the flame.

Owing to new construction any fastening means for the mantles such as magnesia rings or the like are entirely eliminated, so 55 that not only is the manufacture of the mantles greatly simplified, but the packing and

shipping and handling thereof by the consumer are rendered very convenient, and waste due to breakage is minimized.

To make my invention more clear the 60 same is illustrated in the accompanying drawing, in which similar reference characters denote corresponding parts and in which Figure 1 is an elevation of my lamp, Fig. 2, an enlarged cross section on line 2-2 of 65 Fig. 1, Fig. 3, a top plan view of the burner tube, Fig. 4, an elevation of a part of the burner showing a modified construction and Fig. 5, a vertical section of a part of another modified burner and of a limp mantle 70 seated thereon.

The new lamp comprises the usual Bunsen *a* of well known construction, a burner tube *b* and a limp or rag mantle *c*. The burner tube *b* which is adapted to be removably 75 mounted on the Bunsen tube *a* is closed on its top or dome shaped and provided with small central perforations *d* therein, and with a plurality of small openings *d'* in the circumference of the upper part thereof. 80

The circumferential openings are uniformly distributed in substantially equidistantly arranged vertical rows. The limp or soft mantle *c* which has an entirely closed top is advantageously made flaring downwardly and long enough to project below the lowermost row of perforations. The object of making it flaring is to provide a large enough free space around the burner tube, enabling an unobstructed passage for the 90 combustion gases and also to provide a sufficiently large opening through which the burner tube may be freely passed without touching the mantle. The reason for making the mantle longer than the perforated 95 part of the burner is to confine the flames within the mantle.

The rag mantle is made of such a size and so chemically treated that when burnt off by the consumer it will contract to a size suitable for the particular size burner. 100

In use, the mantle is slipped over the burner so as to rest with its top on top of the burner tube. It is then burnt off and after opening the gas cock and on ignition, the 105 flames of the burning gas jets will be directed against the mantle, producing an uninterrupted incandescent surface surrounding the flame from the sides and top.

The top of the burner is made to conform 110 in shape as much as possible with the shape of the top of the mantle and is therefore con-

vex and formed with rounded edges, so that the mantle will, when slipped over it or taken off, not be apt to be damaged and will find a smooth rest thereon.

- 5 While the burner is in operation the top flame, by its pressure, will raise the mantle whose weight is negligible from the burner and hold it practically suspended in the air, as a result of which dark spots, which would 10 occur at points of contact with the burner, will be avoided.

Inasmuch as it is desired to make the limp mantle flaring in order to enable its being readily and quickly put over and removed 15 from the burner tube, the flames must be made to vary in length in accordance with the flare of the mantle in order to enable the mantle to extend through like zones of the different flames, so that a uniformly illuminated 20 surface will be attained.

This I accomplish by graduating the openings d^2 of the different rows of the burner tube, *i. e.*, enlarging them proportionately in a downward direction (Fig. 4), so that the 25 flames will be correspondingly elongated.

In order that the mantle may easily center itself on top of the burner tube when slipped over it, the bunch c' on the inner surface of the top of the mantle, which is formed by 30 drawing the ends of the threads together when closing the top, is utilized. This bunch is stiffened by tying around it a thread or thread c^2 (Fig. 5). This stiffened bunch is adapted to enter a crater or depression e' , 35 which I form in the burner top e when the mantle is slipped over the latter. The bunch c' will also serve to hold the mantle surface out of touch with the burner tube, so as to prevent injury to the mantle, and avoid dark 40 or non-illuminated spots.

To insure incandescence of the top of the mantle a plurality of burner openings e^2 around the crater e' of the burner may be provided.

45 A great advantage of my new construction is the simplicity of the construction of both the burner and mantle, eliminating mantle supports. The mantle, free of rings or other rigid pieces can be folded or rolled together 50 in any suitable manner for shipment.

Another advantage is the convenience with

which it can be handled by the consumer. Its slipping over the top of the burner can be performed without touching it with the hands, whereby soiling is avoided, and the 55 life of the mantle prolonged.

What I claim and desire to secure by Letters Patent is:—

1. An incandescent gas lamp, comprising a bunsen, an upright closed top burner tube 60 thereon, having a plurality of burner holes in its circumference and a central burner hole in its top and an incandescent mantle loosely mounted over the closed-top of said burner tube, so as to extend around said 65 burner holes and be capable of rising under the action of the gas issuing from said central hole to be out of contact with said burner tube.

2. An incandescent gas lamp, comprising 70 a bunsen, a closed-top burner tube thereon, having a plurality of burner holes in its circumference and a central hole in its top, and a closed top limp mantle loosely mounted over the closed top of said burner tube so as 75 to extend around said burner holes and be capable of rising under the action of the gas issuing from said central hole to be out of contact with said burner tube.

3. In an incandescent gas lamp, a closed 80 top burner tube having burner holes in its circumference and a crater in its top, and a closed top incandescent limp mantle formed in the center of its top with a stiffened bunch, adapted to enter and rest in said crater when 85 the mantle is slipped over said burner tube and to thereby center the mantle on the latter.

4. In an incandescent gas lamp, a closed top burner tube having a plurality of burner openings arranged in its circumference in 90 vertical rows of graduated size, and a closed top downwardly flaring mantle adapted to loosely fit over the top of said burner and to extend through like zones of the different flames, to produce a uniformly illuminated 95 surface.

In testimony whereof I affix my signature in presence of two witnesses.

JACOB I. ROBIN.
